DESIGN FOR A SCRUBBING, WAXING, AND POLISHING MACHINE

Ernest J. Newcomer, York, Pa., assignor to
Floorola Products, Inc., York, Pa., a corporation
of Delaware

Application February 21, 1945, Serial No. 118,072

Term of patent 14 years

(Cl. D9—2)

To all whom it may concern:

Be it known that I, Ernest J. Newcomer, a citizen of the United States, residing at York, in the county of York and State of Pennsylvania, have invented a new, original, and ornamental Design for a Scrubbing, Waxing, and Polishing Machine, of which the following is a specification, reference being had to the accompanying drawing, forming part thereof, in which

Fig. 1 is a perspective view of a scrubbing, wax-

ing, and polishing machine showing my new design;

Fig. 2 is a side elevational view of the machine; and

Fig. 3 is a top plan view thereof.

I claim:

The ornamental design for a scrubbing, waxing, and polishing machine, as shown.

ERNEST J. NEWCOMER.
